UNITED STATES PATENT OFFICE.

CHARLES J. CONSER, OF CHICAGO, ILLINOIS.

SOFA-BED.

1,139,641.

Specification of Letters Patent.

Patented May 18, 1915.

Application filed April 17, 1914. Serial No. 832,442.

To all whom it may concern:

Be it known that I, CHARLES J. CONSER, a citizen of the United States, and a resident of the city of Chicago, county of Cook, and State of Illinois, have invented certain new and useful Improvements in Sofa-Beds, of which the following is a specification.

My invention relates to a sofa bed that is to a device adapted for use either as a sofa or a bed, the same being adapted, through folding to be converted from one to the other.

The object of my invention is the production of a sofa bed which will be of durable and economical construction, one which may be readily and easily converted from a sofa to a bed and vice-versa, and one which will be efficient and comfortable in use.

Other objects will appear hereinafter.

With these objects in view my invention consists in the combinations and arrangements of parts hereinafter described and claimed.

The invention will be best understood by reference to the accompanying drawings forming a part of this specification, and in which—

Figure 1 is a top plan view of the device in bed form, the side members of the frame of the device being shown in section, Fig. 2 is a substantially central vertical section of the device in sofa form, the foldable sections of the device being shown unfolded into bed form in dotted lines, Fig. 3 is a detail fragmental section illustrating the pivotal connection of the bed bottom with the frame of the device, Fig. 4 is an enlarged fragmental detail illustrating the pivotal connection between the two outer sections of the bed bottom and the connection of the intermediate or central bed section with the legs which support the outer end thereof when in unfolded position, Fig. 5 is an enlarged detail section taken on substantially line $x-x$ of Fig. 1, Fig. 6 is a section taken on substantially line $y-y$ of Fig. 2, Fig. 7 is a section taken on substantially line $z-z$ of Fig. 2, and Fig. 8 is a front elevation of the outer section of the bed bottom, when the latter is in unfolded condition.

The preferred form of construction as illustrated in the drawings comprises a rigid frame consisting of end members 1 which are spaced apart and rigidly connected by transversely extending bars 2, 3 and 4. Arranged in said frame between the end members 1 is a foldable bed bottom consisting of sections 5, 6 and 7 substantially rectangular in form, the adjacent ends of sections 5 and 6 being pivotally or foldably connected by comparatively short links 8, whereas the adjacent ends of sections 6 and 7 are correspondingly connected by comparatively short links 9. The arrangement is such that said bed bottom is adapted to be folded together as shown in full lines in Fig. 2 or extended to form a bed bottom as shown in dotted lines in said figure. Said sections 5, 6 and 7 as well as the connecting links 8 and 9 are of angle iron construction, the contiguous ends of said sections and links overlapping, when the bed bottom is in extended condition, in order to produce a rigid construction, the arrangement, as is obvious, preventing upward "breaking" of the joints in the bed bottom, when the latter is extended.

The links 8 are provided intermediate their ends with laterally projecting studs 10 which loosely engage upwardly opening sockets 11 provided at the inner sides of the frame members 1 in order to pivotally support the bed bottom therebetween. Pivotally secured at 12 to the inner sides of frame members 1 above the sockets 11 are keepers 13 which serve, when the lower ends thereof are in registration with the upper ends of sockets 11, to lock the studs 10 in position in said sockets. By swinging said keepers 13 to effect non-registration of the lower ends thereof with said sockets, disengagement of said studs from said sockets is permitted in order to effect detachment of the bed bottom from the frame of the device if desired. With this arrangement it will be seen that upon folding of the bed bottom from its extended to its collapsed or folded condition the forward end of the section 5 will be moved downwardly and forwardly, said end of said section, during the unfolding or extension of said bed bottom, being moved rearwardly and upwardly. The rearward end of said section 5 is supported upon inclined supports 14 which are secured to the inner sides of the frame members 1 adjacent the rearward edges thereof. Said supports 14 are so inclined and arranged that the rearward end of the section 5 in the movement of the latter during the folding or unfolding of the bed bottom, as just described, will move parallel to itself, said section be-

ing simply shifted or transferred to its dotted line and full line positions as shown in Fig. 2 with the same constantly supported in a substantially horizontal position.

5 Pivoted at 15 between the upper ends of the frame members 1 is a sofa back member 16, the lower end of said back member being free to swing forwardly and rearwardly. Arising from the rearward end of section 5 10 are bars 17, the upper ends of which slidably engage loops or eyes 18 arranged at the rearward side of the back member 16 adjacent the lower edge thereof. The arrangement is such that, in the movement of 15 the bed section 5 as just described, the lower end of the back member 16 will be simultaneously moved therewith, said end of said back member being swung forwardly in the forward movement of said section and rearwardly during the rearward movement of 20 said section. This is of advantage in that the section 5 may be moved rearwardly so as to be flush with the rearward edges of the member 1 without the back member 16 interfering with the rearward end portion of 25 the bed bottom, when in use. Without this arrangement it is clear that the lower end of the back member 16 would assume a position forward of the rearward end of the 30 section 5 and thus would prevent the utilization of the rearward portion of said bed section as a bed bottom. Upon the member 17 are arranged forwardly extending angularly pieces or flanges 19 which serve as 35 supports for the inner end of the section 7, when the bed bottom is in folded condition.

The bed section 6 carries a sofa seat member 20 which is rigidly fixed to transversely extending bars 21 which are secured at their 40 ends to arms 22 which depend from the side bars of said section 6 when the latter is in unfolded position. Said seat 20 is thus spaced from the bed bottom so as to not interfere with sagging of the bed bottom as 45 is the case when the bed is in use. A rectangular flexible strip 23 of fabric connects the forward edge of seat 20 with the upper edge of the bar 2 serving to close the gap which is formed between said edge of said 50 seat and said bar, when the device is used as a sofa.

The outer end of the section 6, when the device is unfolded into bed form, is supported by legs 24. The upper ends of said 55 legs 24 are pivotally connected by pivot pins 25 with the depending portions 22 of the section 6, said pivot pins projecting from said portions 22 and loosely engaging with elongated slots 26 formed in the upper ends 60 of legs 24 as clearly shown in Fig. 4. With this arrangement, when the device is unfolded, after the legs 24 contact with the floor or ground, the outer end of the section 6 will continue to move downwardly 65 slightly, or a distance corresponding with

the length of the slots 26. Projecting from the portions 22 are also studs 27 adapted, upon the relative downward movement of the outer end of the section 6, as just described, to engage recesses 28 provided in 70 the upper ends of the legs 24 and thus serve to lock said legs in operative position. Said legs will, by gravity, normally assume vertical positions, and during the folding movement of the section 6, the pins 27 will 75 move automatically out of engagement with the recesses 28 so as to permit of the rocking of said legs to the position shown in full lines in Fig. 2. Said legs 24 are connected by a bar 29 which secures simultaneous rocking of said legs, said bar 29 also serving as a weight to insure rocking of the lower ends of said legs to forward position so that the slotted upper ends of said legs will be in alignment with the studs 27 when the section 80 85 90 95 100 105 110 115 120 125 130 135 140 145 150 155 160 165 170 175 180 185 190 195 200 205 210 section 7, the legs 30 will swing to operative position and be locked in this position, and upon folding movement of said section, said legs will be automatically unlocked and 5 swung to folded position as shown in full lines in Fig. 2.

Pivotedly secured at 37 upon the legs 30 are members for releasably locking the sections 6 and 7 together in folded relation. 10 Each of said fastening devices comprises a flexible strap 38 at the outer end of which is carried a perforated metallic strap or plate 39, the perforations in the members 39 being adapted to engage with laterally 15 projecting studs 40 provided at opposite sides of the section 6 as clearly shown in Figs. 1 and 2.

Arranged at the inner sides of the frame members 1 are spring arms 41 secured to 20 said members at 42. The spring arms 41, when the bed bottom is folded together, are engaged by laterally projecting studs 43 provided upon the section 7 being rocked downwardly by contact with said studs to 25 produce a condition of tension, the tension of said spring arms tending to unfold the bed bottom and to this extent facilitates the manual unfolding of the bed bottom when the device is in use.

30 Provided at the outer side of the bar 36 connecting the legs 30 are handles 43' which facilitate folding or unfolding of the bed bottom and provided at the inner edge of the seat 20, when the latter is in folded position is a hand piece or strap 44 which is also provided to facilitate the manual folding or unfolding of the bed bottom.

With a construction as set forth it will be seen that in the folding of the device 40 from bed forming condition to sofa forming condition the section 7 is first swung or folded to position over the section 6 as shown in dotted lines in Fig. 2, the same being releasably locked in this position by the members 38-39 engaging with the studs 40. In 45 the interlocking of members 38-39 with the studs 40, it is, of course, necessary to swing the former on their pivots 37 until said members extend laterally from the legs 30, whereupon the flexible strips 38 of said members 50 will permit of the latter being swung downwardly to the desired engaging position. In this folding of the section 7 the legs 30 automatically unlock themselves and rock to the folded position shown. Next the section 6 together with the section 7 are rocked or folded to position above the section 5 or 55 to the position shown in full lines in Fig. 2, the legs 24, in this operation, being automatically unlocked and folded to the position shown in full lines in said figure. During the last folding operation the section 5 is moved forwardly and downwardly and the sofa back member 16 is simultaneously 60 rocked forwardly to meet the rearward edge 65

of the seat member 20 as shown. In the unfolding of the device the process or procedure just described is simply reversed.

While I have illustrated and described the preferred form of construction for 70 carrying my invention into effect, this is capable of variation and modification without departing from the spirit of the invention. I, therefore, do not wish to be limited to the precise details of construction set 75 forth, but desire to avail myself of such variations and modifications as come within the scope of the appended claims.

Having described my invention what I claim as new and desire to secure by Letters 80 Patent is:

1. In a structure of the class described, the combination of a frame; a foldable bed bottom connected with said frame so as to be adapted to be folded to position in said 85 frame or unfolded to a position extending forwardly from said frame, said bed bottom consisting of a plurality of foldably connected sections; a connection between the innermost of said sections and said frame 90 whereby, when said bed bottom is unfolded, said section will be moved rearwardly and, when said bed bottom is folded, said section will be moved forwardly; a sofa back member mounted in said frame to permit of forward and rearward movement of the lower 95 end thereof; and a connection between said end of said back member and said section of said bed bottom whereby, said parts will move forwardly and rearwardly in unison, 100 substantially as described.

2. In a structure of the class described, the combination of a frame; a foldable bed bottom connected with said frame so as to be adapted to be folded to position in said 10 frame or unfolded to a position extending forwardly from said frame, said bed bottom consisting of a plurality of foldably connected sections; a connection between the innermost of said sections and said frame 11 whereby, when said bed bottom is unfolded, said section will be moved rearwardly and, when said bed bottom is folded, said section will be moved forwardly; a sofa back member mounted in said frame to permit of forward and rearward movement of the lower 115 end thereof; and a connection between said end of said back member and the rearward end of said section of said bed bottom whereby said parts will move forwardly and rearwardly in unison, substantially as described.

3. In a structure of the class described, the combination of a frame; a foldable bed bottom connected with said frame so as to be adapted to be folded to position in said 125 frame or unfolded to a position extending forwardly from said frame, said bed bottom consisting of a plurality of foldably connected sections; a connection between the innermost of said sections and said frame where-

by, when said bed bottom is unfolded, said section will be moved rearwardly and, when said bed bottom is folded, said section will be moved forwardly; a sofa back member 5 mounted in said frame to permit of forward and rearward movement of the lower end thereof; an arm arising from the rearward end of said section of said bed bottom; and a loop at the lower end of said back 10 member with which engages the upper end of said arm whereby said parts will move forwardly and rearwardly in unison, substantially as described.

4. In a structure of the class described, 15 the combination of a frame; a foldable bed bottom comprising a section foldably connected with said frame whereby, when said section is moved to unfolded position, the same will be moved rearwardly and, when 20 said section is moved to folded position, the same will be moved forwardly; a sofa back member mounted in said frame to permit of forward and rearward movement thereof; and a connection between said back 25 member and said section whereby said parts will move forwardly and rearwardly in unison, substantially as described.

5. In a structure of the class described, the combination of a frame; a foldable bed bottom connected with said frame so as to be 30 adapted to be folded to position in said frame or unfolded to a position extending forwardly from said frame, said bed bottom consisting of a plurality of foldable connected sections; a connection between the innermost of said sections and said frame whereby, when said bed bottom is unfolded, said section will be moved rearwardly and, when said bed bottom is folded, said section will be moved forwardly; a sofa back member 35 mounted in said frame to permit of forward and rearward movement of the lower end thereof; and a connection between said back member and said section of said bed bottom whereby said parts will move forwardly and 40 rearwardly, substantially as described.

In testimony whereof I have signed my name to this specification in the presence of two subscribing witnesses.

CHARLES J. CONSER.
